FLASK CAR

James D. Sample, Birmingham, Ala., assignor to
McWane Cast Iron Pipe Co., Birmingham,
Ala.

Application October 10, 1936, Serial No. 105,116

9 Claims. (Cl. 105—367)

This invention relates to new and useful improvements in flask cars employed in plants for manufacturing cast iron pipes and the like.

These cars are designed to carry four flasks each and are employed for transporting the flasks from one point to another in the plant. It is very necessary that these flasks be handled as gently as possible because of the long slender cores used in making the castings. Any slight 10 jarring of the flask may cause sand to fall off the core bar and the result will be a spoiled casting and a damaged core bar.

Among the several objects of my invention are to provide a car of skeleton construction whereby 15 the sand and the gates are able to fall through the car at the shake out point; to provide such a car with shields or deflectors which will direct any sand, which may drop from the flasks while in transit, away from the rails; to provide cushioning means for supporting the flasks on the car; to provide the car with hooks at opposite ends for use in lifting the car and transferring the same from one track to another, and to provide a car which is of simple and light construction and therefore requires very little effort 20 to be pushed along the track.

With these and other objects in view which will more fully appear, the nature of the invention will be more clearly understood by following the description, the appended claims, and the several views illustrated in the accompanying drawings.

In the drawings:

Figure 1 is a top plan view of a flask car 35 constructed in accordance with my invention,

Figure 2 is a horizontal sectional view thereof,
Figure 3 is a side elevation of the car,

Figure 4 is an end elevation thereof,

Figure 5 is a vertical cross section taken on 40 the line 5—5 of Figure 1, and

Figure 6 is a perspective view showing in separated relation one of the transverse beams and portions of the longitudinal beams.

Like reference numerals designate correspond- 45 ing parts throughout the several figures of the drawings.

Referring to the accompanying drawings, my invention embodies a car body A and supporting wheels B adapted to be moved along rails 5, 5. The body A is of skeleton form and includes spaced longitudinal beams 6, 6 and spaced trans- 50 verse beams 7, 7.

The longitudinal beams 6 which are disposed directly above the rails 5, are each formed of 55 sheet metal and are of inverted U-shape in cross

section to include flat vertical edge portions 8, 8 and a connecting hood portion 9. Angle iron braces 10, 10 are rigidly attached by welding or other means to the inner faces of the vertical edge portions 8, the horizontal flanges 11, 11 of the braces projecting towards each other in the horizontal plane containing the lower edges of the beams. The ends of each beam 6 are closed by plates 12, 12 and rigidly attached to these plates are hooks 13, 13 for use in hoisting and transferring the car from one track to another.

The transverse beams 7 project beyond the longitudinal beams 6 and are each of I-beam construction. The lower portions thereof are formed with upwardly projecting recesses 14, 14 to receive snugly the hood portions 9, 9 of the longitudinal beams 6, the edges of the recesses being welded to said hoods. Rigidly secured to the head of each transverse beam are spaced chocks 15, 15 and secured to and extending along 20 the upper faces of the transverse beams are cushioning pads 16 of rubber or other material.

Intermediate cross braces 17, 17 which are preferably of angle iron construction, are located intermediate the transverse beams 7, 7 and are 25 rigidly secured by welding or other means to the lower faces of the horizontal flanges 11 of the longitudinal beams. End cross braces 18, 18 which are preferably of angle iron construction, are located at points between the ends of the 30 longitudinal beams and the transverse beams and are rigidly connected to the lower faces of the horizontal flanges 11 of the longitudinal beams by welding or other means.

Spaced pairs of bearings 19, 19 which are dis- 35 posed directly under the cross beams 7, 7 are bolted to the lower faces of the outer horizontal flanges 11 of the longitudinal beams, and journaled in these bearings are transverse axles 20, 20 to which are fixed the wheels B. The wheels 40 B are located directly below the longitudinal beams 6 and have their upper portions projecting into said beams between the flanges 11, 11 thereof.

In order to prevent the longitudinal beams 6 from becoming depressed by a load of flasks, I have provided each beam with vertical braces 21, 21 which are located in register with the transverse beams 7 and the bearings 19. These braces are seated upon the upper faces of the outer flanges 11 of the longitudinal beams and their upper edges contact the inner faces of the beams 6.

From the foregoing, it will be observed that 50 four flasks may be positioned on the transverse 55

beams 7, 7; that the chocks 15 serve to act as guides in placing flasks on the car and maintain the flasks in parallelism on the car; that the cushioning pads function to reduce the shock to the flasks when being placed on the cars and vibration of the flasks when the car is moving, thereby lessening the tendency of sand to fall off the core bars and reducing the loss of sand from the flasks to a minimum; that the wheels 10 and the rails are protected from falling sand by means of the inverted U-shaped longitudinal beams; that the sand and gates are able to fall through the skeleton car at the shake out point, and that the car may be easily lifted and transported 15 from one track to another.

It is of course to be understood that the details of structure and arrangement of parts may be variously changed and modified without departing from the spirit and scope of my invention.

20 I claim:

1. In a flask car, the combination with a skeleton body comprising a pair of spaced longitudinal beams of inverted U-shaped cross section, and spaced transverse beams rigidly connected to the upper faces of the longitudinal beams; of spaced pairs of bearings secured to the longitudinal beams; a transverse axle journaled in each pair of bearings; one said axle being disposed beneath each transverse beam, and supporting wheels 30 journaled on the axles and located centrally below the longitudinal beams.

2. In a flask car, the combination with a skeleton body comprising a pair of spaced longitudinal beams of inverted U-shaped cross section, and spaced transverse beams rigidly connected to the upper faces of the longitudinal beams; of spaced pairs of bearings secured to the longitudinal beams; a transverse axle journaled in each pair of bearings; one said axle being disposed beneath each transverse beam, and supporting wheels journaled on the axles and located centrally below the longitudinal beams.

45 3. In a flask car, the combination with a skeleton body comprising a pair of spaced longitudinal beams of inverted U-shaped cross section and including vertical edge portions, angle irons secured to the inner faces of said vertical portions and including inwardly extending horizontal flanges located in the horizontal plane containing the lower edges of the beams, and spaced transverse beams rigidly connected to the upper faces of the longitudinal beams; of spaced pairs of bearings secured to the outer flanges of the longitudinal beams; a transverse axle journaled in each pair of bearings; and supporting wheels journaled on the axles and located centrally below the longitudinal beams, the upper portions of the wheels 60 being located within the longitudinal beams and between the horizontal flanges thereof.

4. In a flask car, the combination with a skeleton body comprising a pair of spaced longitudinal beams of inverted U-shaped cross section and including vertical edge portions, angle irons secured to the inner faces of said vertical portions and including inwardly extending horizontal flanges located in the horizontal plane containing the lower edges of the beams, and spaced transverse beams rigidly connected to the upper faces of the

longitudinal beams; of spaced pairs of bearings secured to the outer flanges of the longitudinal beams; a transverse axle journaled in each pair of bearings; transverse braces connected at their ends to the flanges of both longitudinal beams; and supporting wheels journaled on the axles and located centrally below the longitudinal beams, the upper portions of the wheels being located within the longitudinal beams and between the horizontal flanges thereof.

5 5. In a flask car, the combination with a skeleton body comprising a pair of spaced longitudinal beams of inverted U-shaped cross section, and spaced transverse beams rigidly connected to the upper faces of the longitudinal beams; of spaced chocks rigidly attached to the upper face of each transverse beam; spaced pairs of bearings secured to the longitudinal beams; a transverse axle journaled in each pair of bearings; one said axle being disposed beneath each transverse beam, and supporting wheels journaled on the axles and located centrally below the longitudinal beams.

6. In a flask car, the combination with a skeleton body comprising a pair of spaced longitudinal beams of inverted U-shaped cross section, and spaced transverse beams rigidly connected to the upper faces of the longitudinal beams; of cushioning pads secured to and extending along the upper faces of the transverse beams; spaced pairs of bearings secured to the longitudinal beams; a transverse axle journaled in each pair of bearings; and supporting wheels journaled on the axles and located centrally below the longitudinal beams.

35 7. In a flask car, the combination with a skeleton body comprising a pair of spaced longitudinal beams of inverted U-shaped cross section, and spaced transverse beams rigidly connected to the upper faces of the longitudinal beams; of end plates closing the ends of the longitudinal beams; hooks secured to the outer faces of the end plates; spaced pairs of bearings secured to the longitudinal beams; a transverse axle journaled in each pair of bearings; and supporting wheels journaled on the axles and located centrally below the longitudinal beams.

40 8. In a flask car, the combination with a skeleton body comprising a pair of spaced longitudinal beams of inverted U-shaped cross section, and spaced transverse beams rigidly connected to the upper faces of the longitudinal beams; of spaced pairs of bearings secured to the lower faces of the longitudinal beams at points directly below the transverse beams; a transverse axle journaled in each pair of bearings; and supporting wheels 45 journaled on the axles and located centrally below the longitudinal beams.

9. In a flask car, the combination with a skeleton body comprising a pair of spaced longitudinal beams of inverted U-shaped cross section, and spaced transverse beams rigidly connected to the upper faces of the longitudinal beams and having notches in their under surfaces to partially embrace said longitudinal beams; of spaced pairs of bearings secured to the longitudinal beams; a transverse axle journaled in each pair of bearings; and supporting wheels journaled on the axles and located centrally below the longitudinal beams.
